UNITED STATES PATENT OFFICE.

HENRY SCHMASEN, OF ST. LOUIS, MISSOURI.

SASH-BALANCE.

SPECIFICATION forming part of Letters Patent No. 423,881, dated March 18, 1890.

Application filed December 16, 1889. Serial No. 333,974. (No model.)

To all whom it may concern:

Be it known that I, HENRY SCHMASEN, of St. Louis, Missouri, have made a new and useful Improvement in Sash-Balances, of which 5 the following is a full, clear, and exact description.

The improvement relates to that class of sash-balances wherein a spring-actuated pinion and rack are employed; and it consists in 10 the special construction and combination of parts, as is hereinafter set forth and claimed, aided by the annexed drawings, making part of this specification, in which—

Figure 1 is a sectional elevation showing 15 the improved balance in position; Fig. 2, a face view of the balance-frame; Fig. 3, a plan of the balance, and Fig. 4 an elevation showing a modified arrangement of the improved balance.

20 The same letters of reference denote the same parts.

The leading feature of the construction is combining the rack, the pinion, the pinion-actuating spring, the barrel, the head, and the 25 lock substantially in the same plane, and in employing the pinion for a double purpose—namely, for coacting with the rack in raising and lowering the sash and also as a ratchet to co-operate with the lock to hold the 30 sash at any desired level. From this peculiar construction two special advantages are obtained—a simpler mechanism and a stronger more durable one as compared with a sash-balance construction wherein the locking 35 mechanism is at the side of and separate from the pinion. By utilizing the pinion for the two purposes named a more compact structure is obtained and there is no tendency to twist or to turn the structure laterally in its place 40 in the window-frame, and thereby to rack it more or less, as is the case when the locking mechanism is at one side of the spring-containing case.

In the annexed drawings, A represents an 45 ordinary sash, and B an ordinary window-jamb.

C represents the rack, and D the pinion. The pinion is attached centrally to the bar-

rel E, which contains the spring F and is closed by the head G and journaled upon the 50 shaft H, which in turn is journaled in the sides i i of the frame I. The spring is of the customary form and is combined with the barrel and head in the usual manner.

K represents the lock which coacts with 55 the pinion. It is attached to a lever k, pivoted at k' to the frame I. When it engages with the pinion, that part is prevented from turning, and the sash is thereby fastened. Owing to the central position of the pinion in the 60 frame I, there is no tendency in the operation of the device to turn the barrel, so that it shall bear unevenly in its bearings, and when the lock drops into the pinion the shock incident to the arresting of the movement of the 65 pinion is transmitted evenly to the barrel-bearings.

In the present instance the pinion is shown applied to the jamb and the rack to the sash. These positions may be respectively reversed, 70 the pinion being attached to and traveling with the sash and the rack attached to the jamb, as in Fig. 4.

The spring by means of a suitable key inserted in the opening h in the shaft can be 75 wound, so that the spring shall be properly adjusted within the barrel to act to balance the sash in the usual manner. The pawl L and ratchet l are used in the customary manner to prevent the unwinding of the spring. 80

I claim—

In a sash-balance, the combination of the rack C on the sash, the barrel E, having pinions D and the spring F within and journaled in the window-jamb, the pivoted lock 85 K, having handle k, and the pawl L and ratchet l to prevent the unwinding of the spring, all combined and coacting in the manner and for the purposes set forth.

Witness my hand this 11th day of December, 1889.

HENRY SCHMASEN.
